DISPLAY RACK

William D. Rhodes, 6244 W. Roven, Chicago 46, Ill., and
Joseph R. Forrest, 421 N. Sangemon Place, Chicago 22, Ill.

Filed May 20, 1963, Ser. No. 74,949

Term of patent 14 years

(Cl. D80—10)

FIG. 2

FIG. 1 is a front perspective view of a display rack embodying our new design; and,

FIG. 2 is an elevational view taken from one side thereof.

We claim:

The ornamental design for a display rack, as shown.
